UNITED STATES PATENT OFFICE.

EDWARD KAYE, OF MOON, PENNSYLVANIA, ASSIGNOR TO THE PHOENIX
GLASS COMPANY, OF PITTSBURG, PENNSYLVANIA.

DESIGN FOR A SHADE.

SPECIFICATION forming part of Design No. 29,130, dated August 2, 1898.

Application filed April 23, 1898. Serial No. 678,673. Term of patent 14 years.

To all whom it may concern:

Be it known that I, EDWARD KAYE, a citizen of the United States of America, residing in Moon township, in the county of Beaver 5 and State of Pennsylvania, have invented a certain new Design for a Shade for Gas and Lamp Fixtures; and I do hereby declare the following to be a full, clear, and exact description of the invention, such as will enable others skilled in the art to which it applies to make and use the same.

This invention has relation to a design for a shade for gas and lamp fixtures, and is particularly adapted for use with gas-burners of 15 the well-known type of "Welsbach" burners.

The design which constitutes the subject-matter of the present application is shown in the accompanying drawing, wherein the figure is a side elevation of the shade.

The shade comprises a concavo-convex body 20 part and a neck which flares outwardly from its junction with the body part of the shade, both the body and the neck being formed with rounded ribs radially arranged according to the pattern known as a "melon" shape, the 25 ribs on the body terminating in segments or rounded bases above the lower edge of the shade.

Having described my invention, I claim—

The design for a shade herein shown and 30 described.

In testimony whereof I have affixed my signature in presence of two witnesses.

EDWARD KAYE.
